UNITED STATES PATENT OFFICE.

FRANK F. WOELFEL, OF CHICAGO, ILLINOIS, ASSIGNOR TO CHICAGO PORTRAIT COMPANY, OF CHICAGO, ILLINOIS, A CORPORATION OF ILLINOIS.

DESIGN FOR PICTURE GLASS OR SIMILAR ARTICLE.

Application filed October 1, 1923. Serial No. 7,371. Term of patent 14 years.

To all whom it may concern:

Be it known that I, FRANK F. WOELFEL, a citizen of the United States, residing at Chicago, in the county of Cook and State of Illinois, have invented a new, original, and ornamental Design for Picture Glass or Similar Article, of which the following is a specification, reference being had to the accompanying drawing, forming part thereof.

In the drawing, Fig. 1 is a front elevation, showing my new design applied to a picture glass or similar article; Fig. 2 is an end view looking in the direction of the arrow 2, in Fig. 1; Fig. 3 is a side elevation look-

ing in the direction of the arrow 3, in Fig. 1; Fig. 4 is a central, vertical section thereof, taken on the line 4—4 of Fig. 1; Fig. 5 is an end view, looking in the direction of the arrow 5 in Fig. 1; Fig. 6 is a horizontal section taken on the line 6—6 of Fig. 1; Fig. 7 is a horizontal section taken on the line 7—7 of Fig. 1; Fig. 8 is a horizontal section taken on the line 8—8 of Fig. 1; and Fig. 9 is a detail section taken on the line 9—9 of Fig. 1.

I claim:

The ornamental design for picture glass or similar article, as shown.

FRANK F. WOELFEL.
